(57) **CLAIM**

The ornamental design for a bag as, shown and described.

DESCRIPTION

FIG. 1 is a front perspective view of a bag showing our new design;
FIG. 2 is a front view thereof;
FIG. 3 is a rear view thereof;

FIG. 4 is a side view thereof;

FIG. 5 is an opposite side view thereof;

FIG. 6 is a top view thereof; and,

FIG. 7 is a bottom view thereof.

The even-length broken lines within the shaded area represent stitching. The even-length broken lines immediately adjacent to the shaded area define the bounds of the claimed design and form no part thereof. The even-length broken lines depicting the remainder of the bag show features that form no part of the claimed design.
